[57] CLAIM

The ornamental design for a bait station, as shown and described.

DESCRIPTION

FIG. 1 is a perspective view of a bait station showing our new design;

FIG. 2 is a top plan view of the bait station;

FIG. 3 is a bottom plan view of the bait station;

FIG. 4 is a side elevational view of the bait station, the opposite side being a mirror image thereof;

FIG. 5 is a side elevational view taken from a view at 30° rotation from the view of FIG. 4, the opposite side view being a mirror image thereof;

FIG. 6 is a side elevational view taken from a view at 30° rotation from the view of FIG. 5, the opposite side view being a mirror image thereof;

FIG. 7 is a side elevational view taken from a view at 30° rotation from the view of FIG. 6, the opposite side view being a mirror image thereof;

FIG. 8 is a side elevational view taken from a view at 30° rotation from the view of FIG. 7, the opposite side view being a mirror image thereof; and,

FIG. 9 is a side elevational view taken from a view at 30° rotation from the view of FIG. 8, the opposite side view being a mirror image thereof.
